UNITED STATES PATENT OFFICE

121,244

DESIGN FOR A TABLE AND SEAT UNIT

Andrew L. Henkel and Burke M. Ewing, Chicago,
Ill., assignors to The Brunswick-Balke-Collen-
der Company, Chicago, Ill., a corporation of
Delaware

Application April 10, 1940, Serial No. 91,572

Term of patent 14 years

To all whom it may concern:

Be it known that we, Andrew L. Henkel and Burke M. Ewing, both citizens of the United States and both residing in the city of Chicago, in the county of Cook, State of Illinois, have jointly invented a new, original, and ornamental Design for a Table and Seat Unit, of which the following is a specification, reference being had to the accompanying drawing forming a part thereof.

Figure 1 is a side elevational view of a table and seat unit showing our new design;

Figure 2 is a front elevational view thereof;

Figure 3 is a top plan view thereof.

We claim—

The ornamental design for a table and seat unit, as shown.

ANDREW L. HENKEL.
BURKE M. EWING.
